CERVICAL COLLAR

John L. Bond, P.O. Box 1306,
North Wilkesboro, N.C. 28659

Filed Jan. 12, 1970, Ser. No. 20,882

Term of patent 14 years

Int. Cl. D24—04

U.S. Cl. D83—1

FIG. 1

FIG. 2

FIG. 3

FIG. 4

FIG. 1 is a front elevational view of a cervical collar embodying my new design;

FIG. 2 is a side elevational view of the cervical collar of FIG. 1;

FIG. 3 is a rear elevational view of the cervical collar of FIGS. 1 and 2; and

FIG. 4 is a cross-sectional view taken along line 4—4 of FIG. 2.

I claim:

The ornamental design for a cervical collar, as shown.
